CLOSURE DEVICE FOR RENDERING
BOTTLES NONREFILLABLEManuel Diaz y Diaz, Habana, Cuba, assignor of
sixty one-hundredths to Alberto Calas Oquendo,
Habana, CubaApplication March 20, 1943, Serial No. 479,843
In Cuba March 5, 1943

2 Claims. (Cl. 215—30)

This invention relates to non-refillable bottles and like containers, and particularly to a non-refillable closure of disc valve type.

This invention has for its object to provide an improvement in non-refillable closure, consisting in mounting the valve casing almost completely outside the bottle neck and with only a small deep portion thereof fitted in the bottle mouth to center the valve casing, and in making the disc valve with a peripheral edge at its recessed lower face so that its contact with its seat formed by the bottom of the valve casing will be firm and safe about the bottom central opening, whereby I obtain a simpler valve-casing structure and a more efficient operation of the disc valve, thereby adding efficiency to the closure to prevent refilling of the bottle.

The invention is described with reference to the figures of the accompanying drawing, of which:

Fig. 1 is a diametral vertical section view of a bottle neck provided with a non-refillable closure embodying the improvement forming the subject-matter of this invention, in its raised or sealed position.

Fig. 2 is an outer elevational view of the same bottle neck, the bottle neck and the closure being partly cut away to show the automatic locking device for the closure.

Fig. 3 is a sectional view similar to that of Fig. 1, showing the bottle neck in its inclined position and the position of the closure parts in the liquid-discharge position.

Fig. 4 is a perspective detailed view, partly cut away, of the top portion of the closure cover.

Fig. 5 is a perspective detailed view of the holed disc obturating the top of the valve casing.

Fig. 6 is a perspective detailed view of the valve casing.

Fig. 7 is a perspective detailed view similar to Fig. 6, showing a half of the valve casing diametrically cut away.

Fig. 8 is a perspective detailed view of the improved disc valve.

Figs. 9 and 10 are respectively a plan view and an edge view of the catch ring forming the device for automatically locking the closure upon the bottle neck.

In the drawing, 1 indicates a bottle neck which has adjusted at its mouth a small deep portion of the bottom of a device of plastic material in the shape of a cylindrical cup 2 having a central hole 3 at its bottom portion and a peripheral recess 4 at its lower edge to fit on the mouth of the bottle neck 1 and at the same time to rest on a packing washer 5 disposed on the upper edge of bottle

neck 1. The inner space of the cup 2 serves as a lodging for a free valve consisting of a solid disc 6 of a diameter slightly smaller than the inner diameter of the cylindrical body of the cup 2 to permanently allow the passage of liquid thereabout in any inclined position of the bottle, with the peculiarity that the lower face of the disc 6 is recessed to form an annular peripheral edge 7 whereby its contact with the bottom portion of cup 2 serving as a seat for same is more firm and secure than would be if the lower face of the disc 6 were entirely plain.

The upper peripheral portion of the bottle neck 1 has screw threads 8 and thereon is threadedly adjusted a cylindrical cover 9 made of glass or another plastic material provided with an inner threaded groove 10 adapted to be screwed on the bottle screw threads 8 until allowing the lower edge of a larger lower portion 9' of the cover 9 to rest on a marginal rim portion 11' formed on an annular edge 11 provided on the bottle neck 1, said cover 9 having at its upper edge an inner horizontal flange 12 which is adapted to fit on an outer horizontal flange 13 formed on the lower edge of another cylindrical cover 14 of smaller diameter than the cover 9 and situated above. The cover 14 is provided near its lower edge with a horizontal partition 15 which has near the inner surface of cover 14 four inter-equidistant openings 16 (Fig. 4), the cover 14 having at its outer surface a screw thread 17 adapted to threadedly receive the threaded groove of a thread cap 18, preferably metallic, which is adjusted on the upper edge of the upper cover 14 through the intermission of a compressible disc 19 to prevent liquid overflow in the closed position of the cap 18.

Between the lower edge of the upper cover 14 and the upper edge of the cup 2 is interposed a glass or another plastic material disc 20 through the intermission of an upper packing washer 21 and another lower packing washer 22, said disc 20 having a central hole 23 and four smaller equidistant holes 24 arranged in circular alignment about the central hole 23 (Fig. 5), said disc 20 having also at its lower face four pointed projections 25 disposed alternately to the four encircling holes 24, the function of said projections 25 being to prevent the disc 6 from adhering by its upper face to the lower face of the disc 20 upon the bottle being inclined. The upper cover 14 is so placed relatively to the disc 20 that the four openings 16 of the partition do not vertically register the four encircling holes 24 of the disc 20, to which end both the cover 14 and the disc 20 are secured in fixed position by means of a

pointed projection 26 formed at any point of the lower edge of the upper cover 14 and fitting in a hole 27 formed in the disc 20.

Between the horizontal flange 28 joining the lower cylindrical cover 9 and its enlarged lower portion 9', and the annular edge 11 of the bottle neck 1 there is provided an annular hollow space 28 adapted to receive a metallic catch ring 29 which, as shown in Figs. 9 and 10 of the drawing, has cut away therefrom alternatively opposed 10 tongues 30 and 31 which are alternatively inclined upwards and downwards to form opposed catches adapted to engage opposed ratchet gear crowns 32 and 33 formed respectively on the lower face 15 of the horizontal flange 28 and on the upper face of the annular edge 11.

Assuming the catch ring 29 placed on the annular edge 11 in the position on which its downward catches 31 engage the upper ratchet gear crown 33 of the annular edge 11 of the bottle neck 1, the lower cover 9 is screwed on the bottle neck 1, by causing it to rotate to the right or in a clockwise direction until the lower edge of the enlarged portion 9' of said cover 9 comes to rest on the upper face of the annular edge 11 on its marginal rim portion 11', and the upwardly directed catches 30 of the catch ring 29 come to engage the lower ratchet gear crown 32 of the horizontal flange 28, whereupon the lower cover 9 will remain locked and it will be impossible to unscrew the lower cover 9 to withdraw it from the bottle neck 1, the catch ring thus affording an effective locking means for undetectably securing the non-refillable closure to the bottle neck 1, and the lower cover 9 must be broken away in order that the bottle may be refilled.

The present invention constitutes a further development of the bottle closure described in the copending application Ser. No. 478,339 of March 8, 1943.

What I claim is:

1. In a closure device for rendering a bottle non-refillable, the combination of a cup-shaped element having its bottom wall provided with a central hole and also with an angular recess at its peripheral edge forming a flat radial shoulder adapted to seat against the mouth of a bottle, a disc valve of smaller diameter than the inner diameter of said cup-shaped element and provided with a circular recess in one face loosely placed within said cup-shaped element, with the annular edge formed by said circular recess directed downwardly and engaging the bottom of said cup-shaped element, a disc provided with a central hole and with several smaller holes arranged circumferentially thereabout and also with a series of pointed projections at its lower face positioned on the upper edge of said cup-shaped element, a cylindrical cover provided at its lower end with an outwardly extending flange, the lower face of which engaging the top of said last named disc, said cylindrical cover having a horizontal partition in its lower end provided with a series of equidistant peripheral holes and also having at its lower end a pointed projection entering a

matching aperture in said disc, said last named pointed projection being arranged in such a position on said cylindrical cover that upon assembly of the cover and disc the small holes in the latter will be out of registration with the holes in said horizontal partition, and a second cylindrical cover for receiving in its interior the serially aligned first mentioned cover, disc, and cup-shaped member with the disc valve loosely placed within the latter, said second cylindrical cover having at its upper end an inwardly extending flange engaging the upper face of the outwardly extending flange on said first named cover, the lower end of said second cylindrical cover being adapted to receive the upper end of the neck of the bottle and having means adapted to non-removably secure said second cylindrical cover and therewith the entire closure device to the bottle.

2. In a device of the character described, the combination with a bottle having a threaded neck, of a cup-shaped element having its bottom wall provided with a central hole and also with an angular recess at its peripheral edge forming a flat radial shoulder bearing against the upper end 20 of the neck of the bottle, a disc valve of smaller diameter than the inner diameter of said cup-shaped element and provided with a circular recess in one face loosely placed within said cup-shaped element, with the annular edge formed 25 by said circular recess directed downwardly and engaging the bottom of said cup-shaped element, a disc provided with a central hole and with several smaller holes arranged circumferentially thereabout and also with a series of pointed projections 30 at its lower face positioned on the upper edge of said cup-shaped element, a cylindrical cover provided at its lower end with an outwardly extending flange, the lower face of which engaging the top of said last named disc, said 35 cylindrical cover having a horizontal partition in its lower end provided with a series of equidistant peripheral holes and also having at its lower end a pointed projection entering a matching aperture in said disc, said last named pointed projection being arranged in such a position on said cylindrical cover that upon assembly of the cover and disc the small holes in the latter will be out of registration with the holes in said horizontal partition, a second cylindrical cover for receiving 40 in its interior the serially aligned first mentioned cover, disc, and cup-shaped member with the disc valve loosely placed within the latter, said second cylindrical cover having at its upper end an inwardly extending flange engaging the upper 45 face of the outwardly extending flange on said first named cover, the lower end of said second cylindrical cover being provided with interior threads engaging the threads on said threaded neck, and means arranged between the lower end of the second cylindrical cover and the neck of the bottle rendering the second cylindrical cover and therewith the entire closure structure non-removable when the second cylindrical cover has been threaded home on said neck.

MANUEL DIAZ Y DIAZ.
